CORNELIUS J. BROSNAN, OF SPRINGFIELD, MASSACHUSETTS, ASSIGNOR OF
TWO-THIRDS TO W. E. WRIGHT AND H. A. GIBBS, OF SAME PLACE.

TACK-FEEDING DEVICE.

SPECIFICATION forming part of Letters Patent No. 329,268, dated October 27, 1885.

Application filed July 20, 1885. Serial No. 172,032. (No model.)

To all whom it may concern:

Be it known that I, CORNELIUS J. BROSNAN, a citizen of the United States, residing at Springfield, in the county of Hampden and State of Massachusetts, have invented new and useful Improvements in Tack-Feeding Devices for Nailing and other Machines, of which the following is a specification.

This invention relates to improvements in tack-feeding devices for nailing and other machines, the object being to provide an improved tack feeder and reservoir combined, whereby headed tacks and nails are separated from a mass and delivered into a suitable chute or conduit, which conveys them to suitable devices for use in securing buttons to shoes or for nailing the latter, or for other purposes.

In the drawings forming part of this specification, Figure 1 is a perspective view of a tack-feeding device embodying my improvements. Fig. 2 is a transverse section on the line $x-x$, Fig. 1, and including a side view of the supporting-bar and means for rotating the reservoir. Fig. 3 is an enlarged section of a portion of the reservoir and its supporting-ring, showing the position of a tack about to enter the chute and the end of the tack-guiding finger.

In the drawings, E indicates a bar having an arm, w , (a part of which is shown in Fig. 2,) by which arm the said bar is suitably secured in a fixed position on or near any machine which is to be served by the within-described tack-feeding devices. Bar E is of suitable metallic construction, and in it are provided suitable bearings for the shaft c , on which is fixed a ratchet-wheel, s . A lever, y , having a bifurcated end, is hung loosely on said shaft astride of the ratchet wheel, and is provided with a suitable pawl (not shown in the drawings) to engage with said wheel. The lever y is given a vibratory motion by suitable connection with the machine with which the feeding device may be connected, whereby the shaft c and the tack-reservoir, which is connected to the latter, are given an intermittent rotary motion. On the bar E is secured the ring A, in the upper face of which are formed two annular grooves—an upper one (lettered v) and a lower one, in which the edge

of the bottom m of the reservoir rotates, so as to bring the inner side of said bottom in a plane with the face of the groove v , in order that any tacks which may pass from the reservoir, as hereinafter described, may unobstructedly slide from the latter partially into the groove v outside of the reservoir, and subsequently entirely from the latter and said groove into a chute, as hereinafter set forth. The bottom of the reservoir is of disk form, and its diameter corresponds substantially with that of the reservoir B. A short central hub on its under side gives it a proper bearing on which to rotate on bar E, and from its upper face there projects upward a hollow hub, n , whose upper end is screw-threaded, as shown. The bottom m is connected with the shaft c by the usual spline and key or keys, or in any other suitable manner whereby they are made to rotate together, said bottom and the herein-after-described cup-shaped top constituting the reservoir. The top of the reservoir B is in the form of an inverted cup, and is secured on shaft c by a key and spline, as shown, and is connected with the hub n on the bottom m by a screw-threaded boss, z , which screws onto the end of said hub. By said means of connecting the bottom to the top of the reservoir the edge of the side thereof is brought close against the bottom and adequately secured for proper operation. The reservoir has a suitable opening in its top, through which tacks or nails are introduced, and in its side is formed a series of slots, a , standing at right angles to its plane of rotation, whose lower ends terminate over the bottom m , and are at the latter point enlarged, giving them the form of an inverted T or of a tack standing on its head. Just above the lower edge of the reservoir a groove, e , is formed, into which the end of a finger, D, extends, as shown in Figs. 1 and 3. Said finger is secured in a fixed position on any convenient part of the machine. At an opening in the raised border of the groove v is secured a chute or trough, h , which is of proper form to receive the heads of tacks therein, their bodies projecting upward through the slot in its upper side.

The operation of the above-described improvements in providing a line of tacks in

the chute *h*, for use on any machine to which they may be conveyed thereby, is as follows: The reservoir, having been supplied with tacks *d*, Fig. 3, is given an intermittent rotary motion, as aforesaid, whereby the mass of tacks therein is made to roll against the side of the reservoir, (the latter being set at an incline, as shown in Fig. 1,) and such of the tacks as incidentally stand on a line with the slots *a* fall 10 into the latter and slide through the side of the reservoir, taking the position of the tack *d*, Fig. 3. The width of the groove *v* is less than the diameter of the head of the tack, and therefore the head cannot slide out of the 15 lower end of the slot *a*, but is so engaged in the latter that the tack is carried around with the reservoir until it encounters the end of the finger *D*, which so penetrates the groove *e* that the tack is brought against its inclined 20 end, and is thereby guided into the chute *h*, as aforesaid. The aforesaid intermittent rotary motion which is given to the reservoir serves to throw the tacks therein more or less upward away from the lower side of the latter, 25 causing them to slide and tumble back again against the slotted side of the reservoir, and consequently more or less tacks constantly find their way through the slots *a*, and are made to follow the groove *v* toward the chute, 30 keeping the latter continually supplied therewith.

What I claim as my invention is—

1. In tack-feeding devices, a rotating tack-reservoir of cylindrical form, having slots or openings of inverted-T form in the side thereof for the exit of the tacks, said slots extending at right angles to the plane of the rotation of the reservoir, combined with a fixed ring surrounding the lower edge of the latter, within which the reservoir rotates, having the 35 groove *v* beyond the side of the latter, a chute leading from said groove, a fixed finger outside of the reservoir to guide the tacks into said chute, and means, substantially as described, for imparting a rotary motion to the 40 reservoir, substantially as set forth.

2. In combination, the reservoir having the series of inverted-T-shaped slots through its side and the groove *e* therein, the shaft *c*, attached to the reservoir, the ring *A*, having 45 the groove *v* beyond the side of the latter and a chute leading therefrom, and the finger *D*, penetrating said groove *e*, and means, substantially as described, for imparting an intermittent rotary motion to the reservoir, 50 substantially as set forth.

CORNELIUS J. BROSNAN.
